UNITED STATES PATENT OFFICE.

LUCIUS J. PHELPS, OF STONEHAM, MASSACHUSETTS, ASSIGNOR TO PHELPS MOTOR VEHICLE COMPANY, OF STONEHAM, MASSACHUSETTS, A CORPORATION OF MAINE.

ELECTRIC SPARKING IGNITER FOR EXPLOSIVE-MOTORS.

SPECIFICATION forming part of Letters Patent No. 768,687, dated August 30, 1904.

Application filed April 9, 1903. Serial No. 151,840. (No model.)

To all whom it may concern:

Be it known that I, LUCIUS J. PHELPS, of Stoneham, in the county of Middlesex and State of Massachusetts, have invented certain new and useful Improvements in Electric Sparking Igniters for Explosive-Motors, of which the following is a specification.

This invention relates to make-and-break igniting mechanisms for explosion-engines, and includes among its objects the reduction of complication in such structures and an increase of durability, accessibility, and ease of repair.

One of the principal characteristics of the invention is the facility with which the movable electrode which extends into the combustion-chamber of the engine may be removed for inspection, cleaning, or other purpose. In this way I attain an advantage which is characteristic of very few make-and-break sparkers, it being usually a matter of great difficulty and labor to reach and remove the electrode.

Of the accompanying drawings, Figure 1 represents a vertical sectional view of an explosion-engine provided with the improved igniter. Fig. 2 represents a perspective view of parts of the igniter. Fig. 3 represents a perspective view of the igniter-cam. Fig. 4 represents a perspective view of one of the igniter-springs. Fig. 5 represents a horizontal section, partly in plan, showing the mechanism for advancing and retarding the spark with relation to the piston-stroke. Fig. 6 represents a section on line 6 6 of Fig. 1.

The same reference characters indicate the same parts in all the figures.

Referring to the drawings, 10 indicates the cylinder of an explosion-engine having a water jacket or chamber 11 for cooling its walls, a piston 12, a crank-shaft 13, a crank 14, and a connecting-rod 15. The engine, as shown, is a four-cycle one, and hence has a half-speed shaft 16. On this is fixed the igniter-cam 17, which is a projection formed on a collar 18, secured by a set-screw 19 to the shaft 16.

20 is a fixed electrode, and 21 is a sliding

electrode-bar guided in a bearing-sleeve 22, which traverses the water jacket or chamber 11, whereby the heat of the explosion-chamber is prevented from deteriorating the electrode-bar. The upper end of said sleeve projects into the explosion-chamber and is carried close to the tip of the electrode-bar, so as to allow but a slight exposure of said bar within the explosion-chamber. At the lower end of the sleeve 22 is a stuffing-box 23. It will be observed that the sleeve 22 has a bearing on the electrode-bar only at the ends of said sleeve, while between said bearing portions is an enlargement or chamber permitting the accumulation of soot, oil, and other matter which might otherwise obstruct the free movement of the electrode.

The lower end of the electrode-bar 21 passes through a hole in the short leg formed at the head 28 of a substantially L-shaped sliding trip-dog 24, whose lower end enters the crank-casing 25 of the engine through an aperture 26. The electrode 21 has a head 27, residing underneath the head of the trip-dog, and said bar is supported by a spring 29, attached to the dog. This spring has a coil 30, resting against the long arm of the dog 24, an arm 31, residing in a slot 32 in the head 27, and a substantially U-shaped arm or hook 33, passed through a hole 34 in the dog. An advantage of this arrangement is the ease with which a new spring 29 may be inserted in case the old spring breaks. The function of the spring 29 is to allow an upward movement of the dog 24 after the electrode-bar 21 is in contact with the fixed electrode 20 and the jar occasioned by the rapid action of the parts sometimes breaks the spring. The odd springs are preferably furnished with one limb of the arm bent out straight, as represented by dotted lines in Fig. 4, and to attach the spring this straight portion is inserted through the hole 34 and bent downwardly, the arm 31 being snapped under the head 27.

A spring 35, interposed between the dog 24 and stuffing-box 23, depresses said dog toward the cam 17, which latter has a gradual

rise and an abrupt termination which quickly separates the electrodes. By reason of the offset or L-shaped construction of the trip-dog 24 I am enabled to slide the electrode-bar 21 out of its bearing without disturbing the trip-dog. Normally the electrode-bar is in line with a removable cover-plate 45 on the crank-case of the motor, held in place by one or more spring-catches 46, so that should spring 29 break and allow the electrode-bar to drop the latter will not fall out and be lost on the road, as the cover-plate 45 forms a stop which prevents it from fully withdrawing from its bearing-sleeve 22. If it is then desired to remove the electrode-bar, this may be done by removing the cover-plate 45 and sliding the bar fully out of its sleeve. At any time the electrode-bar may be removed in this manner by first removing the cover-plate and releasing the electrode-bar from the arm 31 of spring 29.

To receive the impact of the return of the dog 24 toward the shaft 16 and prevent the dog from indenting the shaft, I provide a buffer-block 36, guided in a recess 37 in the shaft 16 and yieldingly projected outwardly by a spring 38, the head of said buffer-block projecting slightly under the collar 18, as shown in Fig. 3, whereby the outward movement of the buffer-block is limited.

30 The dog 24 normally slides against a projection 39 on the crank-case and a cam-bar 40, its upper end being guided by the lower end of the electrode-bar 21. The dog has a projection 41 on its upper end overlying but normally not meeting the projection 39. If, however, the dog should drop or its lower end be displaced by derangement of the parts or by backward rotation of the cam 17, the projection 41 will hang on the projection 39 and 40 sustain the dog. The lower end of the dog 24 is free to swing to the left as viewed in Fig. 1, to permit the backward rotation of the igniter-cam 17.

The cam-bar 40 is slid horizontally by suitable connections (not shown) under control of the operator and is provided with an inclined surface 42, Fig. 5, which swings the lower end of the dog 24 when the bar is moved, and hence retards or advances the ignition with 45 respect to the stroke of the piston 12. The electrode-bar 21 has a loose fit in the head of the dog 24 to permit the swinging movement of the latter.

The fixed electrode 20 is insulated in a plug 43, and it and the metal of the engine are included in an ordinary igniting-circuit 44. The electrode 20 and the electrode-bar 21 are eccentric to each other, as indicated in Fig. 6, and the former is rotatable in its plug, so as 50 to permit new portions of its contacting surface, which latter, as shown, is transverse to the axis of the plug to be brought into co-operation with the electrode-bar 21.

I do not confine myself to the exact details 55 of construction herein set forth.

I claim—

1. In a make-and-break igniter for explosion-engines, an electrode-actuating device, a trip-dog acted on thereby, an electrode operated on by said trip-dog and removable from 70 operative position independently of the trip-dog, and a resilient connection between said trip-dog and electrode normally holding the latter in operative position.

2. In a make-and-break igniter for explosion-engines, a sliding electrode, and a trip-dog embracing said electrode and having an offset sliding connection therewith permitting the removal of the electrode without removing the trip-dog. 80

3. In a make-and-break igniter for explosion-engines, a sliding electrode, a trip-dog having an offset connection therewith permitting the removal of the electrode without removing the trip-dog, and a spring connecting 85 the electrode and trip-dog and normally holding the former in operative position.

4. In a make-and-break igniter for explosion-engines, a sliding electrode yieldingly projected away from operative position, a 90 spring normally sustaining the same in operative position, and a movable stop to prevent complete withdrawal of said electrode upon the breakage of the spring.

5. In a make-and-break igniter for explosion-engines, an igniter-cam, a substantially L-shaped sliding trip-dog having one arm engaged by said cam, a sliding electrode connected with the other arm, and a spring connecting said trip-dog and electrode. 95

6. In a make-and-break igniter for explosion-engines, a motor having a crank-case provided with a movable cover, an igniter-cam, a trip-dog actuated thereby and having an offset, a sliding electrode engaged with said offset and aligned with said cover when the latter is in normal position, and a resilient connection 105 between said trip-dog and electrode. 100

7. In a make-and-break igniter for explosion-engines, a movable electrode, a trip-dog, and a coiled-wire spring interposed between said members and having a bent arm attaching it to one of the members, said member having means interlocking with the arm and wherefrom the arm is disconnectible by being straightened. 110

8. An electrode-bar, a trip-dog arranged to produce endwise movement of said bar, and a spring interposed between said members and exerting endwise pressure on the electrode-bar, said spring having one arm resting on one of the members and disconnectible therefrom by a swinging movement, and another arm hooked onto the other member. 115

9. In a make-and-break igniter for explosion-engines, a sliding electrode-bar formed with a groove, a trip-dog, and a spring having a coil resting against said dog, an arm occupying said groove, and a second arm detachably hooked onto the dog. 125

130

10. In a make-and-break igniter for explosion-engines, a rotary cam-shaft, a yieldingly-projected buffer thereon, a collar fitted to said shaft and limiting the outward movement 5 of the buffer, and an igniter-cam formed on said collar.

11. In a make-and-break igniter for explosion-engines, a movable electrode, a trip-dog adjustably connected therewith, an igniter-cam acting on said dog, a sliding bar having 10 a cam-incline acting against one side of the dog for moving said dog to advance or retard the ignition, and means yieldingly projecting the dog into coöperative position with respect 15 to said cam-incline.

12. In a make-and-break igniter for explosion-engines, a movable electrode, a sliding trip-dog adjustably connected therewith, an igniter-cam for sliding said dog, an adjusting-cam 20 for varying the position of the end of said dog engaged by the igniter-cam, said dog being movable into and out of coöperative position with respect to the adjusting-cam, and a spring 25 yieldingly impelling said dog into coöperation with said cams.

13. In a make-and-break igniter for explosion-engines, an axially-sliding electrode, a sliding trip-dog extended substantially parallel with said electrode to a trip-point in the 30 opposite direction from the igniting end of the electrode, an igniter-cam acting on said trip-point, and an adjustable connection between said dog and electrode permitting the

axial withdrawal of said electrode from operative position.

14. In a make-and-break igniter for explosion-engines, a movable electrode, a rotary igniter-cam, a stationary trip-dog guide, and a trip-dog interposed between said cam and electrode and slideable on the guide, said trip-dog having a hook overhanging the guide for pivotally sustaining the dog during backward rotation of said cam.

15. In a make-and-break igniter for explosion-engines, a movable electrode, and a plug 45 in the cylinder-wall axially parallel with but eccentric to said movable electrode, said plug having an insulated electrode provided with a contact-face transverse to the axis of the plug, said insulated electrode being manually 50 adjustable rotatively in the plug to present said contact-face in fresh contacting relations with the movable electrode.

16. In a make-and-break igniter for explosion-engines, a motor-cylinder, a sliding electrode-bar entering the combustion-chamber thereof, and a bearing for said electrode, said electrode and bearing being relatively so constructed as to form a collecting-chamber between them.

In testimony whereof I have affixed my signature in presence of two witnesses.

LUCIUS J. PHELPS.
